(57) **CLAIM**

The ornamental design for a car phone holder, as shown.

DESCRIPTION

FIG. 1 is a top left perspective view of a car phone holder showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dashed broken lines depict portions of the car phone holder that form no part of the claim design.
